UNITED STATES PATENT OFFICE

2,108,470

FLOOR TROWELING MACHINE

Harold S. Boulton, Chicago, Ill.

Application December 28, 1936, Serial No. 117,843

10 Claims. (Cl. 94—45)

My invention relates to troweling machines and particularly to an improvement on the construction shown in my copending application, Serial No. 29,901, filed July 5, 1935, Patent No. 2,065,560.

5 An object of my invention is to provide means for effecting a reciprocating movement of the troweling plate or plates as distinguished from a rotary movement such as disclosed in my copending application heretofore referred to. 10 While such movement has been considered to be desirable, its accomplishment has been found to be difficult, due to complications of design and increase in weight and cost of the necessary apparatus. An object of my invention is to bring 15 about the desired movement by the use of mechanism of extreme simplicity and relatively light weight.

Collateral to the desired reciprocating movement, I provide for a simultaneous rotating movement, thus simulating with substantial exactness the hand troweling movement of an experienced operator. The rotative movement also has another advantage that will be discussed hereinafter.

25 The invention will be more readily understood by reference to the accompanying drawings; in which,

Fig. 1 is a side elevation of a troweling machine constructed in accordance with my invention;

30 Fig. 2 is an enlarged transverse vertical sectional view;

Fig. 3 is a sectional view on the line 3—3 of Fig. 2;

Fig. 4 is a sectional view on the line 4—4 of Fig. 2;

35 Fig. 5 is a sectional view through a modified form of troweling apparatus and;

Fig. 6 is a sectional view on the line 6—6 of Fig. 5.

40 In the drawings I have illustrated a motor and frame 10 having an operating handle 11. To the hub 12 of the motor frame is connected, through a thrust-bearing 13, a frame comprising an inner ring 14, arms 15 and an outer ring 16. A horizontal portion of the frame, joined to the described part by means of screws 17, comprises the cross pieces 18 and the outer ring 19.

45 Within the cross pieces I provide slots 20, two being provided in each cross arm and extending 50 parallel to the longitudinal axis of the arm.

Trowel plates 21, four of which are shown, formed as segments of a circle, are each provided with two upstanding studs 22 that project through the slots 18. Springs 23 resting against the plates 55 at one end and against washers 24 at the other end

serve to support the plates in their spaced relation. The outer studs on each plate project upwardly beyond their motion-limiting nuts 25 and terminate in rollers 26 that engage in the cam groove 27 in a cam plate 28 that is pinned to the 5 motor drive shaft 29.

A lug 30 and a latch 31 provide for locking the frame and its associated parts against rotation.

The operation is as follows:

With the rotation of the motor, the cam plate 10 28 will serve to reciprocate the trowel plates or shoes, the different positions being shown in Fig. 3, assuming a cam groove of the form shown; that is, one in which one reciprocation is brought about for each revolution of the motor shaft. The driving force of the cam plate will tend to rotate the entire frame on its thrust-bearing and thus there will be combined rotary and reciprocating movement of the trowels. If the rotation is not desired, the latch 31 may be dropped and the parts 20 will operate merely by reciprocation. This rotary motion has an advantage in that it will prevent the piling up or accumulation of cement between the edges of the trowel plates and will simulate the motion of a workman in troweling. It will be 25 understood, of course, that in addition to the reciprocating and rotary movement, the entire machine will be propelled forward by the workman, thus adding a third movement to the plates.

In the construction shown in Figs. 5 and 6 the 30 motor frame remains the same and this is likewise true of the troweler frame, the latter consisting of an inner ring 32, arms 33, outer ring 34 and cross pieces 35, 36, 37 and 38 and outer ring 39. The cross piece 35 is provided with a slot 35 40 parallel to the long axis of the cross piece. The arm 37 is provided with a slot 41 that is eccentric to the long axis of the piece while the arms 36, 38 have slots 42, 43 that are also eccentric, but slightly less than the slot 41. A single trowel 40 plate 44 is provided with four upstanding studs 45, 46, 47 and 48 that extend through the slots 40, 41, 42, 43 respectively, springs 49 being interposed between the plate and the cross pieces to provide a resilient mounting. The stud 45 extends upwardly and carries a roller 50 working in a groove provided in the cam plate 51 that is pinned to the motor shaft.

It will be noted that the rotation of the motor 50 and the cam plate will cause a movement of the trowel plate that is a combination of reciprocation and oscillation. Of course, if desired, the motion may be straight reciprocation by making all the slots parallel to a single line of move- 55

ment, but the motion described is considered preferable for troweling action.

It is obvious that I have described but one unit of a machine that may include a number of 5 cam plates, all having a desired reciprocating movement, and I wish it understood that such additional plates, or divisions of the plate shown, is contemplated.

The shape, form and disposition of the trowel 10 plates, is unimportant and these features, together with those relating to the method of bringing about reciprocation, may be varied within the skill of the mechanician.

I claim:

15 1. In combination, a frame having a horizontal member providing a slot, a trowel plate having a portion projecting through said slot, a motor, a plate having a cam groove secured to the motor shaft, the upwardly projecting portion of the 20 trowel stud engaging said groove.

2. In a troweling machine, the combination of 25 a frame providing horizontal cross pieces having slots, a trowel plate having studs projecting through said slots, and a motor having a cam plate adapted to engage a stud and effect reciprocation of the trowel plate in a path defined by the slots.

3. In a troweling machine, the combination of 30 a frame providing horizontal cross pieces having slots, a trowel plate having studs projecting through said slots, spring means between the trowel plate and cross pieces, and a motor having a cam plate adapted to engage a stud and effect reciprocation of the trowel plate in a path defined by the slots.

4. In a troweling machine, the combination of 35 a frame providing horizontal cross pieces having slots, at least one of which is eccentric to the longitudinal axis of the pieces, a trowel plate having studs projecting through said slots and a motor having a cam plate adapted to engage a stud and effect reciprocation of the trowel plate in a path defined by the slots.

5. In combination, a frame providing a plurality of angularly disposed slots, a plurality of 40

trowel plates beneath the frame, said plates having upwardly projecting studs engaging said slots, a motor and a cam rotated thereby and engaging said studs for effecting motion of said plates in paths defined by said slots. 5

6. In combination, a frame providing slots, a trowel beneath the frame having studs projecting upwardly into said slots, a motor supported on the frame, and means between the motor and the trowel for effecting reciprocation thereof in 10 the path defined by said slots, and means for mounting said frame for bodily rotation.

7. In combination, a frame having horizontal members providing slots, a trowel plate having studs projecting upwardly into said slots, a 15 motor, means operated by the motor for effecting movement of the plate, and means for mounting said frame for rotation relative to said motor.

8. In combination, a frame providing a plurality of angularly disposed slots, a plurality of 20 trowel plates beneath the frame, said plates having upwardly projecting studs engaging said slots, a motor for reciprocating the slots in an angular relation to each other through said slots, and means for mounting said frame for rotation 25 relative to said motor.

9. In combination, a frame providing a plurality of angularly disposed slots, a plurality of 30 trowel plates beneath the frame, said plates having upwardly projecting studs engaging said slots, a motor and a cam rotated thereby and engaging said studs for effecting motion of said plates in paths defined by said slots, and means for mounting said frame for rotation relative to said motor. 35

10. In combination, a frame providing slots extending radially from the center of the frame, a trowel beneath the frame having studs projecting upwardly through said slots, a motor supported on the frame, and means operated by the motor and above said slotted frame for effecting reciprocation of the trowel in the path defined by said slots. 40
